(57) **CLAIM**

The ornamental design for a writing utensil, substantially as shown and described.

DESCRIPTION

FIG. 1 is an isometric view showing the front, part of one side and part of the top of the writing utensil showing my new design;

FIG. 2 is an elevational front view thereof;

FIG. 3 is an elevational view of one side, the other side being a mirror image thereof;

FIG. 4 is an elevational view of the bottom thereof; and,

FIG. 5 is an elevational view of the top thereof.

The stippled shading shown in the top in FIGS. 1, 2, and 3 is meant to represent a contrast in color.
